UNITED STATES PATENT OFFICE

2,078,110

IGNITING SYSTEM

Richard Tröger, Berlin-Zehlendorf-Mitte, Germany, assignor to General Electric Company, a corporation of New York

Application March 7, 1934, Serial No. 714,517
In Germany March 31, 1933

2 Claims. (Cl. 175—363)

My invention relates to igniting systems for current rectifiers of the arc discharge type, particularly for igniting systems in which a high tension discharge apparatus is employed, and its 5 object is the provision of an improved and simplified igniting apparatus of this type.

A considerable disadvantage of current rectifiers of the arc discharge type employing high tension igniting means is the complexity of the 10 ignition apparatus. The apparatus is rendered especially complex by reason of the fact that, in the case of polyphase rectifiers, a special Tesla type transformer is required for each discharge receptacle.

15 In accordance with my invention this disadvantage is obviated in that the closing of the ignition circuit takes place directly at the arc discharge device and not, as was hitherto the case, when individual Tesla transformers were employed, at the primary side of the transformers.

20 My invention will be better understood from the following description when considered in connection with the accompanying drawing and its scope will be pointed out in the appended claims.

25 Referring to the drawing, Fig. 1 is a diagram of a polyphase rectifier circuit in which my invention has been embodied; Fig. 2 is a diagram illustrating the use of arc discharge devices as switching means in the circuit arrangement of 30 Fig. 1; Fig. 3 is a diagram showing an embodiment of the invention similar to that of Fig. 1 but incorporating transformer means for high ignition discharge voltages; and Fig. 4 is a diagram illustrating the use of arc discharge devices as switching means in the circuit arrangement of 35 Fig. 3.

In the embodiment of the invention shown in Fig. 1 the numerals 10 designate a plurality of arc discharge devices, which may be current rectifiers having cathodes 11 and anodes 12 connected to the secondary windings 13 of a rectifier transformer.

The ignition means for the discharge devices 10 in the embodiment shown in Fig. 1 comprises 45 a condenser 14 arranged to be charged through a rectifier or electric valve 15 by means of a transformer 16 from any suitable alternating current supply. One side 17 or set of plates of the condenser 14 is connected to those electrodes 11, 50 of the discharge devices 10, which operate as cathodes and the other side 18 or coating of the condenser is connected, in desired phase, with the electrodes 12 which operate as anodes.

The alternating connection, in desired phase, of 55 the condenser 14 to a given anode to provide the

high tension discharge is accomplished by means of switching devices indicated by the numeral 19, the devices 19 representing broadly any suitable switching device for the purpose, for example rotating contact arms or members. The resistance 20 serves to limit the condenser discharge current if necessary. The numerals 21 designate 5 protecting choke coils for limiting the high frequency oscillations. Instead of switching means of the rotating arm type it is more advantageous 10 to employ auxiliary discharge devices 22, as shown in Fig. 2, having anodes 23, cathodes 24, and control grids 25 associated with any suitable circuit (not shown) to control the initiation of current flow, in the desired phase, between anodes 15 23 and cathodes 24.

In the operation of the apparatus shown in Fig. 1 and incorporating the preferred switching means including the auxiliary discharge devices 22 as shown in Fig. 2, potentials are impressed 20 in the usual manner from transformer windings 13 on the anodes 12 of the main discharge devices 10. The condenser 14, being in a state of charge through rectifier 15 from the transformer 16, potentials are impressed on the anodes 23 25 of the auxiliary or switching discharge devices 22. As soon as a given one of the auxiliary discharge devices 22 is released, or triggered, in desired phase by the grid control means including the control grids 25, the circuit including the 30 given one of the discharge devices 22 and the condenser 14 is closed to the corresponding anode of the main discharge devices 10, the condenser current then flowing through the auxiliary discharge device and producing an igniting discharge in the corresponding one of the main 35 discharge devices 10.

The whole control apparatus incorporated in the embodiments of the invention illustrated in Figs. 1 and 2 is extremely simple both as regards 40 the apparatus employed and the operation thereof. The shifting or change of phase in the initiation of the ignition discharge, as required for the regulation of voltage in the main circuit, may be accomplished in known manner by suitable arrangements of the contact or switching means which are represented broadly by the numeral 19. For example, in case the switching means 45 19 is of the rotating contact arm type, the stationary contact portion of the switch apparatus 50 may be arranged to be rotated through a partial revolution to secure the desired time of initiation of the ignition discharge. In case auxiliary discharge devices are employed as switching means, as illustrated in Fig. 2, the desired phase 55

shift may be obtained by the provision of any suitable means associated with the control grids 25 for controlling the initiation of current through the auxiliary discharge devices 22.

5 In some cases, with higher voltages, the employment of a special transformer in the igniting circuits is unavoidable. The arrangement suitable in such cases is, then, that illustrated in Fig. 3. In this latter arrangement the condenser 14 10 supplies the ignition voltage, not directly at the anodes 12 of the main discharge devices 10, but through the intermediary of a transformer 26 which includes, besides a primary winding 27, three high potential secondary windings 28 insulated from each other. Each of the windings 28 is connected at one of its terminals to the cathodes 11 of the main discharge devices 10 and is arranged to be connected at its other terminal to a corresponding one of the anodes 12 through 15 the switch means 19.

Further, in the embodiment of the invention illustrated in Fig. 3, another switch means is required, i. e., a switch means 29, for the primary side 27 of the transformer 26. Each time that a 20 secondary winding 28 is connected, through switch means 19, to a corresponding anode 12 of the main discharge devices 10 the switch means 29 must be closed, in addition to the corresponding part of the switch means 19. The 25 switch means indicated broadly in Fig. 3 by the numerals 19 and 29 may be constituted by auxiliary discharge devices 30 and 31 similar to auxiliary discharge devices 22, shown in Fig. 2, and arranged in any suitable manner for grid 30 controlled operation.

In the embodiments of the invention illustrated in Figs. 3 and 4 incorporating the single transformer 26 in the ignition system the control 35 means is considerably simpler than the control means of the igniting arrangements known here-

tofore, in which separate transformers for each one of the main discharge devices were necessary.

What I claim as new and desire to secure by Letters Patent of the United States is:

1. The combination with an igniting system 5 for a current translating apparatus comprising a plurality of main arc discharge devices, of a source of igniting current, a transformer having a primary winding and having a plurality of secondary windings insulated from each other, 10 an arc discharge device adapted periodically to connect said source to said primary winding and to disconnect said source therefrom, and a plurality of arc discharge devices adapted to conduct igniting current from each of said secondary 15 windings sequentially directly to a different one of said main arc discharge devices, said secondary windings each being connected to the corresponding main arc discharge device simultaneously with the connection of said source to said 20 primary winding.

2. The combination with an igniting system 25 for a current translating apparatus comprising a plurality of arc discharge devices, of a source of igniting current, a capacitance means directly connected to said source to receive continually a charging current therefrom, a transformer having a primary winding and having a plurality of secondary windings insulated from each other, switch means adapted periodically to connect 30 said capacitance means to said primary to discharge said capacitance means therethrough, and switch means adapted to conduct igniting current from each of said secondary windings sequentially directly to a different one of said 35 arc discharge devices, said secondary windings each being connected to the corresponding main arc discharge device simultaneously with the connection of said capacitance means to said primary winding.

RICHARD TRÖGER.
